(57) CLAIM

The ornamental design for a coffee machine as shown and described.

DESCRIPTION

1. Coffee machine

1.1 : Perspective

1.2 : Perspective

1.2 : Front

1.4 : Right

1.5 : Left

1.6 : Back

1.7 : Top

View 1.1 is a perspective view of the coffee machine; view 1.2 is a rear perspective view thereof; view 1.3 is a front view thereof; view 1.4 is a right view thereof; view 1.5 is a left view thereof; view 1.6 is a back view thereof; view 1.7 is a top view thereof.

The broken lines show portions of the coffee machine that form no part of the claimed design.

1 Claim, 7 Drawing Sheets
